Primary Examiner — Keith J Wilson(74) *Attorney, Agent, or Firm* — Birch, Stewart, Kolasch & Birch, LLP(57) **CLAIM**

The ornamental design for a nozzle for water purifier as shown and described.

DESCRIPTION

1. Nozzle for water purifier

1.1 : Front perspective view

1.2 : Bottom perspective view

1.3 : Front

1.4 : Back

1.5 : Left

1.6 : Right

1.7 : Top

1.8 : Bottom

1.9 : Reference

1.10 : Reference

Reproduction 1.9 shows a state of use with its adjustable angle; reproduction 1.10 shows another state of use wherein broken lines depict environmental structure and form no part of the claimed design.

1 Claim, 10 Drawing Sheets(56)
